UNITED STATES PATENT OFFICE

ANDREW M. HUNT, OF NEW YORK, N. Y., ASSIGNOR TO STANDARD STOKER COMPANY, INCORPORATED, A CORPORATION OF DELAWARE

STOKER DISTRIBUTING MEANS

Application filed January 27, 1925. Serial No. 5,027.

This invention relates to stokers and particularly to an improved means for distributing coal over the fire by jets of steam or other fluid.

5 In the embodiment of my invention herein illustrated, I have shown a locomotive stoker wherein coal is mechanically conveyed from the locomotive tender to a point in the fire box below the grate and is then elevated 10 through a suitable conduit to a point above the fire where it is acted upon by jets of steam or other fluid which carry and distribute the coal evenly over the fire.

15 Among the objects of my invention is to improve the efficiency of the coal distributing jets by increasing the kinetic energy and carrying power of the steam as it issues from the jet forming openings. For this purpose, I form jet forming openings of progressively 20 increasing area and I so arrange these openings as to obtain a maximum effect on the entire mass of coal delivered to the fire box.

Various other objects and advantages of 25 my invention will appear from the following description taken in connection with the accompanying drawing which shows one embodiment of my invention and wherein Fig. 1 is a side view, partly in section, of the forward end of a stoker disclosing my improved 30 distributing means, Fig. 2 is a plan view of a portion of the structure shown in Fig. 1, Fig. 3 is a section taken on the line 3—3 of Fig. 1, and Fig. 4 is a front elevation of the jet distributing head.

35 Referring to Fig. 1, the numeral 10 represents the rear water leg of a locomotive boiler provided with a feed door opening 11 above the cab deck 12. Coal is carried from the locomotive tender (not shown) by means of a 40 conduit 15 which contains the conveyor screw 16. At the forward end of the conduit 15 is an elbow 18 and in the form of stoker illustrated, the conveyor screw 16 terminates at the elbow and the remainder of the conveying 45 conduit is formed as an upwardly extending slightly expanding section 20 which is free from any conveying mechanism. The section 20 terminates in a discharge mouth 21 which is surrounded by the protective grate 50 22 and is provided with a steam jet distribu-

tor 24. The distributor comprises a distributor head 25 having substantially radial expanding nozzles or openings 26 which are supplied from separate steam chambers 29 formed in the distributor head. Each of 55 these chambers is supplied with steam by a pipe 27 as shown. Each of the pipes is provided with an adjustable valve 28, one only of which is shown, for controlling the supply of steam through the pipe.

60 In practice, the coal from the tender is advanced by the screw to the elbow 18. As it leaves the free end of the screw, it becomes consolidated in a symmetrical stream or core in the elbow and advances around the easy upward curve of the elbow and through the unobstructed section 20 to the mouth 21, where it comes into the path of the steam jets, which issue from the openings 26. As shown in 65 Figs. 2 and 3, these openings are arranged 70 so that the series of jets form a sheet or sheets of propelling fluid which pick up and carry the coal as it issues from the mouth 21 and distribute it over the fire. In the preferred form of my invention, the openings 26 expand laterally, rather than vertically, and in 75 this manner I confine the sheet of propelling fluid to the proper vertical dimensions.

It will be observed that by the present 80 invention there is provided in combination in a locomotive stoker, open-mouthed means for elevating fuel in the combustion chamber in a symmetrical consolidated core, a distributor head adjacent to the mouth of said means and having a wedge-shaped bottom 85 partly overlying said mouth and operative on the fuel core at one side as it rises; and that said distributor head has a steam supply and also a jet forming opening flaring or spreading progressively outward in a horizontal direction and disposed at an angle to the fuel core, the construction being such that the pressure head of steam is rapidly converted into velocity and the jet is spread out fan-wise in such a position as to slice 90 or cut off the top portion of the advancing fuel core immediately after it passes out of the mouth of the elbowed conduit, which, together with the feed screw, is comprised in 95 the said open mouthed means.

I claim:

1. In a locomotive stoker, open-mouthed means for elevating fuel in the combustion chamber in a symmetrical consolidated core, and a distributor head adjacent to the mouth of said means and having a wedge-shaped bottom partly overlying said mouth and operative on said core at one side as it rises, said distributor head having a steam supply and a jet-forming opening flaring progressively outward in a horizontal direction and disposed at an angle to the core of the fuel to rapidly convert the pressure head of steam into velocity and spread the jet fan-wise to slice or cut off the top of the upwardly advancing fuel core.
- 10 2. In a locomotive stoker, open-mouthed means for elevating fuel into the combustion chamber in a symmetrical core, and a distributor head adjacent to the mouth of said means, said distributor head having a steam supply and a passage opening therefrom, which flares laterally and without vertical flaring from its inlet to its outlet for converting the pressure head of the steam into velocity and for spreading a jet of steam therefrom fan-wise so that it is horizontally disposed and at an angle to the core of fuel, said jet operating to slice or cut off the top portion of the upwardly advancing fuel core whose movement is always at substantially right angles to the fan-wise steam jet.
- 20 3. In a locomotive stoker, open-mouthed means for elevating fuel into the combustion chamber in a symmetrical consolidated core, and a distributor head attached to the mouth portion of said means within the combustion chamber of the locomotive and having a wedge-shaped bottom to prevent obstruction of a side portion of the fuel core as it leaves the mouth of said means, said distributor head having a steam supply and a plurality of separate steam chambers above said wedge-shaped bottom, and also a plurality of radially disposed passageways leading from said steam chambers, which passageways flare horizontally from inlet to outlet for converting the pressure head of steam rapidly into velocity and for spreading the jets therefrom into a continuous horizontal sheet which is effective to slice or cut off the top of the upwardly advancing fuel core.
